KNITTING MACHINE

Julius Sirmay, Philadelphia, Pa., assignor to Jacquard Knitting Machine Co., Inc., Philadelphia, Pa., a corporation of New York

Application May 9, 1936, Serial No. 78,920

15 Claims. (CL 66—24)

My invention relates to knitting machines. It is directed particularly to circular knitting machines for knitting fabrics incorporating pattern or design effects, and especially pattern or design effects produced by eyelets, dropped stitches, rib work on a jersey background or vice versa, and the use of yarns of different colors.

It also provides an arrangement for assuring non-interference between the stitch-forming instrumentalities (for example, between the needles of a dial and cylinder) at a loop-shedding station, in a machine arranged to transfer stitches from needles of one needle bank to needles of another bank.

15 Preferably the apparatus is so arranged that in addition to doing pattern work, the machine is capable of forming edges or selvages and borders (for example a racked edge and broad rib border or cuff), and knitting the fabric in the form of 20 individual garment-length pieces, which may be joined together into a continuous length by a draw thread between each two garment-lengths or something of the same sort.

The accompanying drawings illustrate the preferred form of my invention. Fig. 1 is an extremely diagrammatic plan view of a part of the machine, particularly intended to illustrate the relative location of the pattern-controlling mechanism and the cam-controlling mechanism. Fig. 2 is a section thereof adjacent the end of one of the pattern drums. Fig. 3 illustrates diagrammatically the cams that can be assumed to be employed in the machine of Figs. 1 and 2. Figs. 4 and 5 are elevations of the needles I prefer to use in one of the needle banks, with some positions of yarn loops indicated thereon. Fig. 6 is an elevation of a needle like that of Fig. 5 except that it has a shorter butt, Figs. 5 and 6 together being representative of the long and short butt needles referred to hereinafter.

As appears in Figs. 1 and 2, the circular knitting machine illustrated is a rather conventional form of rib machine, the bed 1 and sub-bed 2 of which are supported in some conventional manner, and carry a fixed slotted cylinder 3 and co-operating dial 4 for sliding latch needles 5 and 6, together with a rotary cam cylinder 8 and secondary cam cylinder 9 carrying the cams for reciprocating the cylinder needles 5 and a rotating dial cam cap 10 for reciprocating the dial needles. Relatively, the cylinder needles 5 and dial needles 6 are located as in ordinary rib machines, that is to say with the dial needles working respectively midway between adjacent cylinder needles. In a conventional manner, the needle dial 4 may be

suspended on a vertical post 11 carried by an overhead structure and held against rotation by a dogless mechanism. As indicated by the link or arm 12, I prefer to arrange for the racking of the dial needles for the purpose of forming a desirable edge or selvage, and racking a distance equal to the distance between two adjacent cylinder needles is sufficient for this purpose. To permit a desired location of the pattern mechanism illustrated, the needles 5 are in effect extended by 10 providing say each of them with a sliding needle jack 13. The pattern mechanism illustrated is of a well known type adapted to control each needle, or group of a few adjacent needles, individually and permit the knitting of complex 15 designs of very considerable lengths of repeat. Briefly, this pattern mechanism consists of a number of pattern drums 14 distributed around the axis of the machine as indicated in Fig. 1, each of these drums carrying a perforated paper pattern and being provided with a group of levers 15, hinged and sliding on a cross bar 22, which the drums thrust inwardly underneath the needle jacks 13 as feeler members find perforations in the patterns carried by the drums and thus as 20 cams (for example cams 16, 17 and 18) carried by the secondary cam cylinder 9 pass around the machine, the needles are projected selectively at the call of the pattern sections. The pattern drums 14 are advanced step by step more or less 25 individually by mechanism 19, and at 20 is indicated mechanism whereby the operation of the pattern drums can be discontinued and started again at the call of the machine controller outlined generally at 21 in Fig. 1, and which consists essentially of a series of vertically movable bobbins, controlled by a pattern of paper or otherwise, and which also adjusts the positions of the various cams as its controlling pattern may dictate and as necessary to secure the results desired 30 in any particular fabric. These mechanisms are so well known that the foregoing description will suffice. The cam cylinders 8 and 9 and the dial cam cap 10 are driven synchronously as will be understood; each pattern cylinder 14 is advanced 35 a step to bring a new call to the feelers of its group of levers 15 while each of the lever-operating cams (e. g., 16, 17, 18) is passing the group of needles served by the pattern cylinder 14 immediately in advance; the controller 21 operates 40 in such a manner that when any cam is shifted thereby, it is shifted at substantially the position of this controller, and at this position a few needles may be omitted from both the cylinder and dial.

As before indicated sliding latch needles are used in both the dial and the cylinder. Preferably I employ pattern mechanism to control the needles of only one of the two needle banks, the cylinder bank in the present instance as before indicated. The needles of at least one of the two needle banks are so constructed, or such means are provided, that stitches can be shed and preferably transferred from the needles of one bank to needles of the other; preferably this is at the needle bank controlled by the pattern mechanism, and preferably the needles 5 are provided with side clips 24 for this purpose of transferring to the dial needle 6. As illustrated in Fig. 3, the machine is preferably provided with at least two feeds A and B and a shedding station T; additional feeds and shedding stations can be provided however; usually I provide one shedding station T for each two feeds, distributing these shedding stations uniformly around the machine.

At each feed I provide one of the pattern cams 17, 18 before mentioned, and also I provide one of these cams 16 at the shedding station so as to be able to obtain selective shedding of the loops from the cylinder needles as the particular pattern being knitted may require. It will be observed that the shedding station T is angularly displaced from each of the feeds, that is to say, from each group of devices provided to cause cylinder needles to take yarn, with the result that loops can be selected for shedding entirely independently of the selection of needles to take yarn; for example, a pattern mechanism or pattern mechanisms can be used to control the taking of yarn by the needles and to control the transferring or shedding of loops, one entirely independently of the other. At each feed also a stitch cam 25 is provided to retract the cylinder needles and return the raised jacks 13 to their rest positions after the cams 17 and 18 have passed. The cams move in the direction of the arrow 26. At each feed also is provided at least one stitch cam 27 for the dial needles, and a cam 28 capable of projecting, say, all the dial needles to yarn-taking and clearing positions (where the needle latches are thrust through and beyond the respective loops, so that these old loops will be cast off when the needle is retracted by the stitch cam). Preferably too each feed is provided with at least two yarn guides 29 and 30 movable into and out of action alternately under the control of the controller 21.

At the shedding station, the cylinder needles are provided with a cam or series of cams 33, 34 and 35 for raising the needles to such a position that the clips 24 are thrust into the loops on these needles, and also the dial needles are provided with a cam or series of cams 36 and 37 whereby the dial needles are thrust out at the proper times into the respective clips 24 of the associated cylinder needles, so that as the cylinder needles are thereafter retracted by the cylinder cam 38 the corresponding cylinder stitches are transferred to the dial needles. A cam 39 at the shedding station serves thereupon to return the dial needles to their rest positions. The cylinder cam system 33-34-35 is so placed however above the normal path of the butts 31 and 32 of the cylinder needles 5, that the cylinder needles pass through this shedding station T with their butts in the bye-race 40 without being raised by these cams, unless given a prior initial raising movement. By reason of this bye-race 40, no needle, or substantially no needle, is raised, at the shedding station, to the same elevation as the dial

needles unless a loop is to be shed from it; furthermore by reason of the bye-race 40 all the cylinder needles can be held below the dial needles, as is necessary when racking the dial as mentioned again hereafter; and still further, when a needle is carried up by the cam 33, this needle goes to a certain definite elevation, as might not always be the case were the bye-race 40 omitted and needles permitted to pass the shedding station without transferring by movement of, say, the cam 35 to a lower out-of-action position. The construction with the bye-race 40 therefore assures non-interference between needles 5 and 6 at the shedding station. Also preferably this cam group 33-34-35 is composed of three cams as illustrated, the raising cam 33 being fixed in position, and raising the needles far enough to clear their loops behind their latches but not high enough to cause transferring of the stitches, the cam 35 also being fixed in position and being at the transferring position (or carrying the needles the last step in the transferring operation), and the intermediate cam 34 being movable into and out of operative position, and in operating position spanning the vertical distance between the top of cam 33 and cam 35, so that when in operation cam 34 raises the needles from cam 33 to cam 35 and thereby brings about transferring, but when out of operation permitting the butts 31 and 32 of the cylinder needles to pass from the top of cam 33 direct to the retracting cam 38, that is to say, below the cam 35. As a result, needles passing up the cam 33 when the cam 34 is in operative position, have their loops transferred to the respective dial needles, but needles passing up this raising cam 33 when the cam 34 is in inoperative position, simply have their loops cast off and thus form dropped stitches. At the shedding station T therefore, loops may be shed from the cylinder needles to form a plurality of different kinds of stitches; for example, as described, the transfer stitches and dropped stitches.

The pattern mechanism 14, including the needle-raising cam 16 at the shedding station, provides for selectively raising the needles initially to within the path of the raising cam 33, and therefore permits the shedding of loops from the cylinder needles selectively and individually. The needle raising cams 41 and retracting cams 42 serve to raise the needles far enough to cause the loops of yarn on the needles to open the needle latches and then retract the needles to their normal or rest level with the loops still on the needles.

Various other cams (indicated by double-headed arrows as movable into and out of operative positions) are shown on the drawings. Assuming for the moment that either these other cams are not present, or are held in their inactive positions, it will be apparent that the mechanisms already specifically referred to can be used to do a considerable variety of pattern work. For example: If the dial projecting cams 28 are held in inactive position, and the paper patterns of the pattern mechanism or drums 14 are so constructed as not to lift needles at the shedding station, a jersey fabric can be knitted on the cylinder needles partly from yarn of one color at feed A and partly from yarn of another color at feed B, in accordance with a predetermined design as dictated by the call of the pattern on the needles in advance of the passage of these two feeds. Again, assuming that the dial projecting cams 28 are in action so that all dial

needles take yarn at both feeds A and B and thus knit a jersey fabric or background on the dial needles, rib stitches can be produced in accordance with a predetermined pattern or design, by using the patterns to control the operation of the cylinder needles at either one or both of these feeds. If for example the desired pattern calls for a repeated rib stitching in any given wale, the cylinder needle knitting this wale is permitted (by the pattern mechanism) to pass along the bye-race 40 at the shedding station; when the rib work on this needle is to be discontinued, the pattern mechanism is so perforated that at this time this needle is raised high enough by the cam 16 for its butt to pass on to the raising cam 33 whence it passes over cam 34 and on to cam 35, and thereby its last stitch is transferred to the adjacent dial needle. Again, an eyelet stitch can be made at a selected point in jersey fabric by using the pattern mechanism 14 to cause a needle at this point to rise and take yarn at feed B and immediately pass above the cam 35 at the shedding station so as to shed this yarn on to a dial needle; two (or more) loops can be gathered on a cylinder needle and shed or transferred on to a dial needle to form a larger eyelet, by causing the same needle to take yarn at two or more passes of a feed or feeds over it, before transferring. Particularly for these larger eyelets, I prefer to make the pattern or lever cams at the feeds (e. g., cams 17 and 18) adjustable to two positions, namely, to a higher position where they cause their selected needles to be raised to a clearing height, and to a lower position where they raise their needles to tucking position, i. e., to a position high enough to take yarn from the passing yarn guide, but not high enough to clear their latches through any loops that may be hanging on those needles. This obviously increases the range of patterning or fancy effects that can be knitted. Still further, dropped stitches can be produced at desired places in jersey fabric knit-ted on the dial needles, by withdrawing the cam 34 from action at the transfer section, and using the pattern mechanism to cause the appropriate cylinder needles to take yarn at one or all the feeds, and also pass above the cam 33, whereat the loop or loops is or are cleared below the needle latches, but are shed or cast off the needles without transferring to dial needles inasmuch as the absence of cam 34 permits these needles to pass below rather than above the cam 35.

As before indicated, I prefer to so construct the machine that edges or selvages, and borders of broad rib, and also unpatterned plain fabric can be made without using the pattern mechanism 14, etc., for this purpose, that is to say, by the use of cams alone, the pattern mechanism being held temporarily out of action, say by the use of the mechanism 20, previously referred to, for taking the pattern mechanism out of action at the proper time and restoring it to action again when needed for pattern work. To this end, I provide some of the needles with long butts (such as 31, Fig. 5) and the remainder with short butts (such as 32, Fig. 6), and I provide cams individually movable into and out of operating positions. When the long butt and short butt dial needles and the long butt and short butt cylinder needles are all in action, 1:1 rib stitching is produced. As appears from the foregoing, cams 28 are arranged to project both the long butt needles and the short butt needles of the dial, to clearing positions. A cam 46 at each feed A and B, movable into and out of operating position, is so placed

that when in operating position it projects both the long butt needles and the short butt needles of the cylinder to clearing and yarn-taking position. By the use of cams 28 and 46 therefore, (the pattern mechanism being held out of operation) plain 1:1 rib fabric can be made, the cylinder needles passing the shedding station by way of the bye-race 40. The long butt needles are so placed in the dial and the cylinder that when these needles alone are used, the desired broad rib, say a 2:2 rib, is produced; the short butt needles occupy the intermediate positions in both the dial and the cylinder. Cams 45 at both feeds for the dial needles, and cams 44 at both feeds for the cylinder needles, are so placed (farther away from the dial needles and the cylinder needles than the cams 28 and 46 respectively) as to project only the high butt needles; the cams 45 are preferably movable into and out of operating position (as well as cams 28) so as to permit the discontinuance of knitting on the dial needles at either or both feeds at will (for example, to permit racking, or the knitting of a French welt or the like), and also the cylinder cams 44 (as well as 46) are mounted for movement out of operating position both for the same purposes and also to permit the use of the pattern mechanism on the cylinder needles as before described. To knit a broad rib therefore, the cams 45 and 44 are placed in operative position (cams 28 and 46 are held in inoperative position and likewise the pattern mechanism is held inoperative), with the result that only the long butt needles of the two banks knit; as with the knitting of 1:1 rib, the cylinder needles pass the shedding station by way of the bye-race 40, so that as many rounds of broad rib may be knitted successively as desired.

Preferably I provide a gate cam 47 which is normally held in inoperative position, but when raised to its dotted line position in Fig. 3 will serve to cause all the cylinder needles to pass on to the cam 33. This cam is useful particularly whenever it is desired to transfer all cylinder stitches there may be on to dial needles.

As before explained, the cam 34 when moved to inoperative position, permits all needles passing over the cam 33 to cast off their stitches without transferring those stitches to dial needles. By withdrawing this cam 34 from operating position therefore and holding cam 41 in its dotted line position in Fig. 3, all cylinder stitches can be cast off in a single rotation of the cam cylinder. A cam 48 on the dial, normally held in inoperative position, is movable into a position to project all the dial needles to clearing position at a point where they take no yarn, with the result that when in action all the dial needles cast off their loops, as these needles are retracted by the following cam 49. In view of the ability of the machine to knit 1:1 rib fabric, to knit French welt, and to cast off all stitches from the dial needles and all stitches from the cylinder needles, independently (all the movable cams being movable into and out of action by the controller independently of each other), as well as rack at least the distance between two adjacent cylinder needles, it will be understood by those skilled in the art that a racked edge or selvage can be produced. When knitting a broad rib it is usually desirable to retract the dial needles earlier than when knitting a 1:1 rib. For this reason I usually provide the dial with additional stitch cams 58 movable into and out of operating position. In order to hold the cylinder needles projected with certainty during the knitting of certain of

the plain fabrics, I prefer to provide the cylinder cams 51 for this purpose, these simply holding elevated needles that have been raised by the raising cams in advance of them. These cams 51 can be moved downwardly out of operating position however so as not to interfere with the operations of knitting broad rib and knitting pattern work.

I prefer to move the cam 34 into and out of operation by movement at right angles to the cylinder needles. The other cams adjustable in position can well be moved in directions parallel to their needles, as indicated by the double-headed arrows on those cams in Fig. 3. Various mechanisms for adjusting cams to various positions under the control of such controllers as 21 of Fig. 1, are well known, and various of these mechanisms can be used with this machine. A plate 52 carried by the cam cylinder or dial cam 20 cap at the shedding station, serves to ride on the loops of the cylinder needles as those needles rise to transfer, and thus help to hold those loops from rising unduly high with their needles. Inasmuch as cylinder needles that transfer loops 25 to dial needles have no loops to assure their latches being closed as they are retracted, I prefer to provide a latch closer in the form of a plate or member 54, carried say by the cam cylinder, to pass underneath opened cylinder needle 30 latches and thus raise these latches to closed positions as the needles are retracted by the reTRACTING cam 38 of the shedding station.

As appears from the foregoing, various means for transferring stitches from needles of one bank 35 to needles of the other bank can be employed with my invention, and various forms of transferring needles with clips such as pointed to by 5 and 24 are known. Preferably however I employ the form of needle and clip illustrated particularly 40 in Figs. 4 and 5 and the specific operation thereof indicated by the camming at the shedding station in Fig. 3. This needle illustrated is provided with a slot or depression 55 into which the upper pointed end 56 of the clip normally lies, so that 45 this end 56 of the clip readily passes into the loop 57 hanging on the needle as the needle is raised toward transferring position. Preferably also the forward edge of the needle is provided with a forwardly extending inclined projection 58, beginning at a point on the needle rather well above the end 56 of the clip, and accordingly which 50 serves to draw out the loop 57 in a direction directly away from the edge of the fabric prior to the entry of the end 56 of the clip 24 into the loop. 55 From the upper end 56 of the clip downwardly, this projection 58 retreats toward the back of the needle as it were (see Fig. 5), so that as the needle rises through the loop and the clip 24 carries the loop end still further forward, the leg 59 of the 60 loop 57 is allowed more and more to take a diagonal direction from near the back edge of the needle to the forward edge of the clip 24, so that as the horizontal shoulder 60 on the forward part of the needle, and the adjacent indentation 61 on 65 the forward edge of the clip, come to the loop 57, the loop has been swung rather sidewise as it were (Fig. 4) rather than entirely expanded by reason of its passage over the clip 24, so that the minimum amount of tension has been put on the loop 70 by its passage on to the clip 24, and the opposite leg 62 of the loop now extends downwardly so that a dial needle 6 can be thrust far enough out to pass its hooked end over this leg 62 with certainty. The operation of transferring therefore, 75 with this new needle, is substantially to raise

the needle 5 to a height where the stitch rests on the shoulder 60 (Figs. 4 and 5, this is the needle position on the forward portion of the cam 35, Fig. 3), then project outwardly the cooperating dial needle 6 that is to receive the stitch or loop to place its hook end above the leg 62 of the loop but not necessarily underneath the cross bar 63 of the loop (Figs. 4 and 5, this movement is caused by the cam 36, Fig. 3), then raise the cylinder needle 5 slightly higher so as to place the cross bar 63 of the loop well above the level of the dial needle (this slight upward movement of the cylinder needles is caused by the part 64 of cam 35, Fig. 3), and while the cylinder needle is held in this highest position, moving the dial needle forward another step to place its hook underneath and outside of the cross bar 63 of the loop (this movement being secured by the cam 37, Fig. 3). The transferring is then completed by retracting the cylinder needle (by cam 38, Fig. 3) which leaves the loop on the dial needle as will be understood, and after the end of the cylinder needle has passed below the dial needle, the operation is complete and the dial needle may be retracted to its rest position. This form of needle and clip, and this mode of transferring, secures transference with less breakage of the yarn and greater certainty of transferring than any other form of transferring with which I am familiar.

It will be understood of course that my invention is not limited to the details of construction and operation described above and illustrated in the accompanying drawings, except as appears hereinafter in the claims.

I claim:

1. In a knitting machine, a yarn feeder, a bank of needles, means to cause said needles to knit at said yarn feeder, a second cooperating bank of needles, means to cause the needles of said second bank to take and omit taking yarn at said 40 yarn feeder selectively, and means to cause those needles of said second bank which take yarn to shed their loops selectively at a point angularly displaced from said means which causes the needles of said second bank to take yarn and where no yarn is fed to the needles of said second bank.

2. A knitting machine according to claim 1, wherein the shedding means include means to shed loops from needles of said second bank onto other needles.

3. The subject matter of claim 1, characterized by the fact that said shedding means includes means to shed loops from the needles of said second bank onto needles of said first bank.

4. The subject matter of claim 1, characterized by the fact that said shedding means includes a cam to control needles of the second bank in transferring loops to needles of the first mentioned bank, and a race is provided around said cam through which the needles of the second mentioned bank can travel without shedding loops that are upon them.

5. The subject matter of claim 1, characterized by the fact that said shedding means includes a cam to control needles of the second bank in transferring loops to needles of the first mentioned bank, and a race is provided around said cam through which the needles of the second mentioned bank can travel without shedding loops that are upon them, and said means to cause needles of said second bank to take yarn causes said needles to clear any loop that may be on them at the time.

6. The subject matter of claim 1, character-

ized by the fact that said shedding means includes a cam to control needles of the second bank in transferring loops to needles of the first mentioned bank, and a race is provided around 5 said cam through which the needles of the second mentioned bank can travel without shedding loops that are upon them, and said means to cause needles of said second bank to take yarn causes said needles to clear any loop that may 10 be on them at the time, or, alternately at will, retain a plurality of yarns in their hooks.

7. In a circular knitting machine, a plurality of yarn feeders, a circular bank of needles, means to cause said needles to knit at all said 15 yarn feeders, a second and cooperating bank of needles, means to cause the needles of said second bank to take and omit taking yarn selectively at said plurality of yarn feeders, and means, behind said plurality of yarn feeders 20 and angularly displaced from said means causing needles of the second bank to take yarn, to cause selected ones of those needles of said second bank which have taken yarn to shed their loops at a point where no yarn is fed to 25 the needles of said second bank.

8. The subject matter of claim 7, characterized by the fact that said shedding means includes means to cause loops shed by needles of the second bank to be shed onto needles of the 30 first mentioned bank.

9. The subject matter of claim 7, characterized by the fact that said shedding means includes means to cause loops shed by needles of the second bank to be shed onto needles of 35 the first mentioned bank, and means are provided to cause yarn taken on the needles of said second bank to form knit stitches.

10. The subject matter of claim 7, characterized by the fact that said shedding means includes means to cause loops shed by needles of 40

the second bank to be shed onto needles of the first mentioned bank, and means are provided to cause yarn taken on the needles of said second bank to form knit stitches, or, alternately at will, take a plurality of yarns in their hooks 5 without casting off.

11. In a circular knitting machine, a plurality of cooperating banks of needles, a plurality of yarn guides, means to cause the needles of one of said banks to knit from said plurality 10 of yarn guides, means to cause needles of the other bank to take and omit taking yarn selectively from said yarn guides, a transfer cam means, angularly displaced from said means which causes needles of said other bank to take 15 yarn, and means to selectively move needles of said other bank which have taken yarn, into the path of said transfer cam means.

12. The subject matter of claim 11, characterized by the fact that said transfer cam means 20 includes a cam to project needles from clearing position towards transfer position, said cam being movable out of active position at will to permit needles to clear without transferring their loops.

13. The subject matter of claim 11, characterized by the fact that means are provided to cause needles of said other bank taking yarn to move to clearing position and thereafter cast-off.

14. The subject matter of claim 11, characterized by the fact that means are provided to cause needles of said other bank taking yarn to move to clearing position and thereafter cast-off, or, alternately at will, to take yarn without clearing.

15. The subject matter of claim 11, in combination with cam means, movable into and out of operating position, to cause all the needles of said other bank to move into the path of said transfer cam means.

JULIUS SIRMAY. 40

CERTIFICATE OF CORRECTION.

Patent No. 2,181,105.

November 21, 1939.

JULIUS SIRKAY.

It is hereby certified that error appears in the printed specification of the above numbered patent requiring correction as follows: Page 1, second column, line 8, after the word "purpose" and before the period insert ; if desired, a racking mechanism like, for example, that shown and described in my U.S. Patent No. 1,891,956, December 27, 1932, can be used; and that the said Letters Patent should be read with this correction therein that the same may conform to the record of the case in the Patent Office.

Signed and sealed this 26th day of December, A. D. 1939.

(Seal)

Henry Van Arsdale,
Acting Commissioner of Patents.
